UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

RETAINING DEVICE

Application filed May 19, 1928. Serial No. 279,085.

This invention relates to retaining devices and more particularly to such adapted for connection with draft keys to prevent undesired removal thereof.

The principal object of my invention, generally considered, is the provision of an improved key retainer adapted for application to one or both ends of draft keys for preventing undesired removal or loss thereof.

Another object of my invention is to provide a draft key retainer comprising a looped member fitting over or encircling the end of an associated draft key, the upper and lower portions of said retainer being provided with apertures registering with a corresponding aperture in the associated key for receiving a connecting pin, and an associated pin formed with a head for limiting downward movement thereof and a bifurcated or split end adapted to be spread in place after insertion to prevent undesired withdrawal thereof.

A further object of my invention is the provision of a retainer adapted to be economically manufactured by casting, if desired, and formed of such a size as to fit around an end of a draft rigging key, said retainer preferably being formed with a reinforcing bead or rib around the inner or sill-adjacent side thereof and provided with relatively large apertures through the upper and lower portions thereof, said bead being extended to form bosses around the apertured portions of said retainer, said apertures being preferably elongated and of corresponding forma-

tion whereby said retainer may be applied either side up, and a pin formed with a split end adapted to be spread in place in the direction of elongation of said apertures the other end being headed and formed with a shank portion adjacent said head elongated to fit in the corresponding aperture for preventing turning of said pin.

Other objects and advantages of the invention relating to the particular arrangement and construction of the parts will become apparent as the description proceeds.

Referring to the drawing illustrating my invention, the scope whereof is defined by the appended claims:

Figure 1 is a plan of one form of my re-

tainer, an associated draft key being diagrammatically illustrated by dot and dash lines.

Figure 2 is a side elevation of the retainer shown in Figure 1, the end of the associated key being shown diagrammatically by dot and dash lines.

Figure 3 is an end elevational view of the retainer shown in Figures 1 and 2 detached from the associated key.

Figure 4 is a fragmentary view corresponding to Figure 2, but showing a modification.

Figure 5 is a fragmentary horizontal sectional view on the line 5—5 of Figure 4, looking in the direction of the arrows, the pin only being shown.

Referring to the drawing in detail, like parts being designated by like reference characters, and first considering the embodiment of my invention illustrated in Figures 1, 2 and 3, a retainer 1 is shown applied to one end of an associated draft rigging key 2. Although said retainer is shown applied to a conventional form of horizontal key ordinarily employed with Farlow draft rigging, it will be understood that I do not wish to be limited to such use, as my retainer may be used for other purposes. Although I have shown only one end of the key 2, it will be understood that the other end may either be the same as illustrated and have a retainer applied thereto, or may be headed in a conventional manner, as will be understood.

In the form of my invention illustrated, the retainer comprises just two parts, a looped or washer member 3 and a headed pin 4. The pin is preferably of relatively large diameter corresponding, for example, to a brake hanger pin, whereby it is amply strong and readily manufactured. The loop or washer member 3 is desirably formed by casting, although it may be made in any desired manner and comprises upper and lower approximately triangular portions joined by curved end portions 6, leaving an elongated aperture 7 therebetween adapted to receive the key 2 with normal clearance therebetween. The clearance provided is sufficient to permit application of a washer

over the end of the key and normal angling of said washer in service upon corresponding angling of the associated key 2. The inner side or that adapted to engage the associated sill or cheek plate of a car, is preferably reinforced by beading or ribbing 8 of a width corresponding with the end portion 6 of the retainer, the other sides of the portions 5 tapering to merge into the beading 10 8 at the ends of the looped member 3. Adjacent the central portion of the upper and lower parts 5 of the loop the beading 8 is preferably widened to the other edge of the retainer, as illustrated, to form the bosses 15 9 around the apertures 10 and 11 formed to receive the connecting pin 4. It will be understood that the associated key 2 is formed with a corresponding aperture therethrough.

20 In the embodiment now being considered the lower aperture 11 is elongated to correspond substantially with a flattened frustum of a cone, the vertex being inward of the retainer, whereby when the split or bifurcated end 12 of the pin 4 is expanded in place it will not be necessary to so sharply bend said portions for preventing removal thereof, and when expanded in place, relative turning of the pin is prevented. The 25 other aperture 10 is shown cylindrical to correspond with the cylindrical shank portion 13 of the pin 4.

Referring now to the embodiment of my invention illustrated in Figures 4 and 5, a 30 construction is there disclosed which is identical with the first embodiment, except that the upper portion 5 of the retaining loop 3^a is formed with an aperture 10^a therethrough, corresponding in size and shape 35 with the aperture 11 of the first embodiment, thereby making it impossible to apply the retaining loop 3^a upside down, as either aperture may be used interchangeably for receiving the split end of the pin. The shank 40 4^a of the pin 4^a is formed adjacent the head thereof with an elongated tapering portion 14 formed to correspond with the size and shape of the aperture 10^a. The interfitting between the pin 4^a and the correspondingly formed aperture 10^a results in a 45 construction which prevents the pin from turning with respect to the washer or loop as well as providing for application of said washer with either side up.

50 Having thus described my invention, I claim:

1. A retainer adapted for use with draft keys comprising a looped member fitting over the end of a key, the upper and lower portions 50 of said loop being provided with apertures adapted to register with an aperture near the end of said key, and a pin extending in said apertures said pin being formed with a head 55 limiting downward movement, and a bifurcated end spread in place for preventing un-

desired removal thereof, the aperture receiving said bifurcated end being elongated to prevent relative turning of the pin.

2. A retainer adapted for use with draft keys comprising a looped member fitting over the end of a key, the upper and lower portions of said loop being provided with apertures adapted to register with an aperture near the end of said key, said apertures being elongated and a pin extending therein, said pin being formed with a head limiting downward movement and a bifurcated end spread in place in the direction of elongation of the corresponding aperture for preventing undesired removal thereof, the shank of said pin adjacent said head being correspondingly elongated for preventing turning of said pin and avoiding incorrect application of the retainer.

3. A retainer adapted for use with draft keys comprising a looped member fitting over the end of a key, the upper and lower portions of said loop being provided with outwardly flaring elongated apertures generally corresponding in shape with flattened frustums of cones, said apertures being identical in size and shape whereby the looped member may be applied to the key with either side up, and a pin extending in said apertures, said pin being formed with a head limiting downward movement, an adjacent shank portion corresponding in size and shape with an aperture in said looped member, and a bifurcated end adapted to be spread in place in the direction of elongation of the corresponding aperture in said looped member for preventing undesired removal of said pin.

4. In combination, a draft key apertured near an end thereof, a retainer comprising a looped member fitting over the end of said key, the upper and lower portions of said member being provided with apertures registering with the aperture in said key, said apertures being elongated, and a pin extending therein, said pin being formed with a head limiting downward movement and a bifurcated end spread in place in the direction of elongation of the corresponding aperture for preventing undesired removal thereof, the shank of said pin adjacent said head being correspondingly elongated for preventing turning of said pin and avoiding incorrect application of the retainer.

5. In combination, a railway draft key apertured near an end thereof, a retainer comprising a looped member fitting over the end of said key, the upper and lower portions of said loop being provided with outwardly flaring elongated apertures generally corresponding in shape with flattened frustums of cones, said apertures being identical in size and shape whereby the looped member may be applied to the key with either side up, and a pin extending in said apertures, said pin being formed with a head limiting downward

movement, an adjacent shank portion corresponding in size and shape with an aperture in said looped member, and a bifurcated end spread in place in the direction of elongation of the corresponding aperture in said looped member for preventing undesired removal of said pin.

In testimony whereof I affix my signature.

DONALD S. BARROWS.
